FIG. II.

B. M. Hartman '53
Univ. of Hess

UNITED STATES PATENT OFFICE.

RUDOLPH CONRADER, OF ERIE, PENNSYLVANIA.

POLISHING-MACHINE.

1,213,591.

Specification of Letters Patent. Patented Jan. 23, 1917.

Application filed April 12, 1911. Serial No. 620,658.

To all whom it may concern:

Be it known that I, RUDOLPH CONRADER, a citizen of the United States, residing at Erie, in the county of Erie and State of Pennsylvania, have invented new and useful Improvements in Polishing-Machines, of which the following is a specification.

This invention relates to polishing machines, and consists in certain improvements in the construction thereof as will be hereinafter fully described and pointed out in the claims.

The invention is peculiarly adapted for actuating laps for polishing and as shown is arranged to operate laps similar to that shown in my former application, #597,013. It is preferable to arrange such machines for handling a plurality of laps, also to handle a plurality of laps from the same arbor.

The machine as shown is particularly adapted for polishing pump barrels, and holding devices are shown for conveniently operating upon such barrels.

The invention is illustrated in the accompanying drawings as follows:

Figure 1 is a plan view of the machine. Fig. 2 a side elevation of the machine. Fig. 3 a sectional view of one of the laps on the line 3—3 in Fig. 4. Fig. 4 a section on the line 4—4 in Fig. 3. Fig. 5 an enlarged view of one of the pump barrels detached and with the centering collars thereon. Fig. 6 a section of a fragment of the machine on the line 6—6 in Figs. 1 and 2. Fig. 7 a section on the line 7—7 in Figs. 1 and 2. Fig. 7^a is a section on the line 8—8, the point of view being from the right. Fig. 8 is a section of the machine on the line 8—8 in Figs. 1 and 2, parts of the machine being removed to better show construction. Fig. 9 is a central horizontal section of the feed mechanism and reversing gears, the section being on the line 9—9 in Fig. 11. Fig. 10 a side elevation of the reversing lever. Fig. 11 shows a central section of the arbor and one of the spindles with their bearing and a front elevation of the reversing gear.

The frame of the machine is made up of the two longitudinal bars 1 and 2 which are supported by frames forming legs or supports 3, 4, 5, and 6.

The working barrels 7 (see Fig. 5) are

screw threaded at the ends 8—8 and in order that their bores may be centered with this same thread, I arrange the centering collars 9 on these screw threaded ends and these centering collars or bushings are centered in the machine.

Rest sockets 10 are arranged in the cross frame 11 on the supports 3 and 6. Similar sockets 12 are arranged in the cross pieces 13 supported by the bars 1 and 2. These cross bars 13 are clamped on the bars 1 and 2 by plates 14. The studs 15 extend upwardly between both the sockets 10 and 12 and plates 16 are arranged on these studs so as to engage the collars 9 in the sockets. Nuts 15 are arranged on the studs and by means of these nuts operating on the plates 16, the barrels may be clamped in the sockets and thus be in a position to be operated upon by the laps. The plates 16 are preferably narrow enough so as to be swung sidewise and dropped down into the spaces between the sockets so as to be out of the way in removing and reinserting barrels for operation.

In Figs. 3 and 4, I show in detail one of the laps preferably used in this machine, the same forming the subject matter of my former application heretofore referred to. The laps are formed of the two parts 18—18 which are carried by the plates 20—20 and 21—21. The plates 20 are secured to the head 19. At the opposite end the plates 21 are secured to a screw threaded head 22 and stop bolts 23 are provided for limiting the outward movement of the laps. The screw threaded heads 22 of the laps are screwed onto the ends 24 of the spindles 25. The opposite end of the spindles 25 are squared at 26 and are driven by the arbors 27, the arbors having the squared sockets 28 to receive the squared ends 26 (see Fig. 11). The spindles are carried by the bearing bars 29. These bars are in the form of pipe or tube and have the bearings 30 arranged at their ends. Each spindle 25 has the shoulder 31 at the end adjacent to the lap and a collar 32 is arranged against this shoulder, the washer 33 being interposed between this collar and the bearing 30. At the opposite end the nuts 35 and 36 are screwed on to the end of the spindle 105 and the washer 34 is arranged between these

nuts and the end of the bearing 30. In this way, the end thrust on the spindle is taken care of. A feed frame 37 is slidingly mounted on the bars 1 and 2. Posts 38 extend upwardly from this frame, and the bearing bars 29 are clamped in these posts by means of the set screws 39 so that as the feed frame is moved longitudinally of the machine, the bearing bars are forced end-
wise carrying with them the spindles and laps. The bearing bars slide through bearings 40 arranged on the cross pieces 41 carried by the legs or supports 4 and 5.

It will be noted that as the feed frame 15 is moved longitudinally of the machine, the bearing bars slide through the bearings 40 and carry with them the spindles on which are arranged the laps. It will be observed also that these bearing bars enter the barrels being polished, and in this way, the laps are given a bearing support which follows the laps into the barrel.

The feed frame 37 has the depending posts 42, 43, 44 and 45 (see Fig. 8). Between the 25 posts 42 and 43 are the bearings 46 which rest on the bar 1 and between the posts 44 and 45 are the bearings 47 which rest on the bar 2. Racks 48 are set into the bottoms of the bars 1 and 2 and gears 49 mesh these 30 racks. The gears 49 are fixed on the shaft 50, the shaft being mounted in the bearings 51 on the depending posts of the bearing frame. A handle 52 is arranged at the end of the shaft so that the bearing frame may 35 be fed by hand if desired. This is accomplished by turning the shaft 50 and with it the gears 49, the gears 49 acting on the racks to effect the feeding movement. These gears operating on both sides of the bearing 40 frame insure an even feeding movement at both front and rear of the frame.

I prefer to provide an automatic reverse and feeding mechanism for feeding the bearing frame. This mechanism is as follows: 45 The beveled gear 53 is fixed on the shaft 50. This meshes the beveled gear 54 which is fixed on the shaft 55. The shaft 55 is mounted in bearings on the posts 56 extending downwardly from the bearing frame between the bars 1 and 2. A clutch block 57 is slidingly mounted on the shaft 55 but locked against rotation thereon. The block has the usual ring 58 on which the lever 59 operates. The block is provided with the 55 detents 60 which operate in conjunction with the detents 62 on the face of a gear 63. The gear 63 is loosely mounted on the shaft 55 so that when the clutch is thrown out, the shaft 55 may rotate without operating the 60 gear 63 and vice versa, when the clutch is thrown in, the shaft 55 is made to rotate with the gear 63. The gear 63 meshes the spur gear 64 mounted on a stud 65. The stud 65 is carried between the posts 56 and 65 67, the post 67 extending downwardly from

the feed frame. The gear 64 is fixed on the face of a gear 68 also journaled on the stud 65. The gear 68 meshes a gear 69, the gear 69 being fixed on the shaft 70. The shaft 70 is journaled in bearings in the posts 67. 70 Feed pulleys 71 are journaled on the shaft 70 and are driven in reverse directions by mechanism hereinafter described. These pulleys have the detents 72 which engage detents on the clutch block 73. The clutch 75 block is slidingly mounted on the shaft 70 but locked against rotation by the spline 74. The block has the usual ring 75 on which the lever 77 operates, the lever being provided with the pins 78 for engaging with the ring 80 as shown in Fig. 10.

The operation of the feed mechanism so far as described is as follows: The shaft 70 being driven in one direction or the other, communicates its movement through the series of gears described to the gear 63. With the clutch having the block 57 in engagement, the shaft 55 is driven with the gears and by the feed pulleys 71. The motion of the shaft is communicated to the feed shaft 90 50 by means of the gears 53 and 54. This, therefore, compels a movement of the feed frame along the bars 1 and 2 carrying with it the lap spindles.

The reversing mechanism for the feed is 95 as follows: The lever 77 is pivotally mounted on a post 79 extending downwardly from the feed frame. It is provided with the arms 80. The lever 81 is also pivoted on the post 79, and it is provided with the arms 82, adjusting screws 83 being arranged at the ends of the arm 82. A wheel 84 is pivotally mounted on the lever 81 and engages detents 85 in the end of a plunger 86. The plunger 86 is carried in a socket 87 and is 100 forced outwardly against the wheel 84 by means of the spring 88. The socket 87 is carried by a post 87 extending downwardly from the bearing frame. A reversing rod 89 is carried by the swivel block 90 on the bottom of the lever 81, and as the feeding frame traverses the main frame, this reversing rod 89 contacts the reversing stops 91 and effects a reversing of the feed mechanism. The reversing stops 91 are adjustably mounted in the bars 41 by means of the screws 92.

The operation of the reversing mechanism is as follows: When the rod 89 engages the stop 91, it forces the lever 81 so as to 120 carry the wheel 84 over the dividing point between the detents 85. The adjusting screws 83 are so arranged that they contact the ends 80 of the lever 77 just as the wheel reaches a point beyond the dividing projection between the detents. The lever 77 is therefore not moved with the lever 81 until the roller has passed this dividing point. The influence of the spring operating against the plunger, forces the side of the 125 130

detent against the wheel and this acting as a cam, throws the lever 81 in advance of the movement of the feed mechanism as communicated to the lever through the rod 89 and 5 as the adjusting screw 83 has at this time contacted the end 80 of the lever 77, this movement of the lever 81 through the action of the spring 88 throws the lever 77 so as to slide the clutch block in the opposite 10 pulley. This cam and detent mechanism, therefore, carries the reversing action though independent of the feed itself after the wheel 86 is once carried beyond the dividing projection between the detents. 15 This prevents the stopping of the feed mechanism at a neutral point as might be the case if a movement of this reversing block was dependent entirely upon the feeding movement itself. 20 Arms 93 extending downwardly from the feeding frame form supports for the shaft 94, the shaft 94 being also journaled in the main supports of the machine 4 and 5. Feed drive pulleys 96—96 are mounted on the 25 shaft 94 and locked against rotation thereon by a spline 94^a extending the full length of the shaft. In this way, the feed drive pulleys 96 may travel along the shaft 94 between the arms 93 with the feed frame and 30 still be driven readily by the shaft 94. Belts 97 and 98 extend from the pulleys 96 to the pulleys 71, one of these belts 97 being straight and the other being reversed or twisted so as to give the one pulley 71 a reverse direction of movement from the other 35 pulley 71.

The arbors are driven from the pulley 95 which is mounted on the shaft 94 between the pulleys 96. This pulley is locked against 40 rotation on the shaft 94 by the spline 94^a but is free to slide along the shaft as are the pulleys 96. The shaft 94 is driven by the pulley 99 from any convenient source of power and the movement of the shaft is 45 communicated by way of the pulley 95 and belt 100 to pulleys 101 on the arbors 27, the pulleys 101 being fixed on said arbors by the keys 102 and the belt being arranged over and under the different pulleys 101, as shown 50 in Fig. 8, so as to drive all the spindles. In this way, both the feed movement and the drive movement is delivered to the parts on the feed frame as it travels along the machine to give the feeding movement to the 55 laps, and the drive belts are relieved of any strain that might be incident to feeding them along a drum or other means of communication as is commonly employed in machines driven with a shifting movement.

60 What I claim as new is:

1. In a polishing machine, the combination of a lap made up of sections movable radially under the influence of centrifugal force; a spindle carrying the lap; means for 65 rotating the spindle; and mechanism for

automatically reciprocating the spindle, the speed throughout each reciprocating movement being uniform.

2. In a polishing machine, the combination of a plurality of spindles; means for 70 rotating said spindles; and a common mechanism for axially and automatically reciprocating the spindles in unison, the speed throughout each reciprocating movement being uniform. 75

3. In a polishing machine, the combination of two spindles in alinement; an arbor between the spindles for driving them; and mechanism for axially reciprocating the arbor with the spindles. 80

4. In a polishing machine, the combination of two spindles in alinement; an arbor between the spindles for driving them; and mechanism for automatically reciprocating the spindles with the arbor in an 85 axial direction.

5. In a polishing machine, the combination of two spindles arranged in alinement; laps arranged at the outer ends of said spindles, said laps being made up of sections 90 movable radially under the influence of centrifugal force; an arbor arranged between the spindles for driving said spindles; and mechanism for reciprocating the spindles with the arbor in an axial direction. 95

6. In a polishing machine, the combination of a plurality of arbors; spindles extending from each end of the arbors; and a common mechanism for axially reciprocating the arbors and spindles. 100

7. In a polishing machine, the combination of a work holder; a bearing bar adapted to enter the bore of a tube in the work holder; a spindle journaled in the bearing bar; means for rotating the spindle in the 105 bearing bar; supports for the bearing bar; and means for reciprocating the bearing bar and work holder relatively to each other.

8. In a polishing machine, the combination of a work holder; a bearing bar adapted to enter the bore of a tube in the work holder; a spindle journaled in the bearing bar; means for rotating the spindle in the bearing bar; supports for the bearing bar; and means for reciprocating the bearing bar. 110

9. In a polishing machine, the combination of a work holder; a bearing bar adapted to enter the tube in the work holder; a spindle journaled in the bearing bar; means for rotating the spindle in the bearing bar; a movable support for the bearing bar; a stationary support on which the bearing bar is slidingly mounted; and means for reciprocating the movable support to reciprocate the bearing bar and spindle. 120

10. In a polishing machine, the combination of a work holder adapted to hold a plurality of tubes in parallel relation; a series of bearing bars adapted to enter bores of tubes arranged in the work holder; spindles 130

journalized in the bearing bars; means for rotating said spindles; supports for the bearing bars; and means for reciprocating said bearing bars and work holder relatively to each other.

11. In a polishing machine, the combination of a work holder adapted to hold a plurality of tubes in parallel relation; a series of bearing bars adapted to enter bores of tubes arranged in the work holder; spindles journaled in the bearing bars; means for rotating said spindles; supports for the bearing bars; and a common means for reciprocating the bearing bars in unison.

12. In a polishing machine, the combination of two work holders each adapted to hold a series of tubes in parallel relation, the tubes in one work holder being in alignment with those in the other; a series of arbors arranged between the work holders; a series of bearing bars one at each end of each arbor in alignment with the work holders; spindles journaled in the bearing bars and connected with the arbors; and means for reciprocating the work holders and arbors relatively to each other.

13. In a polishing machine, the combination of two work holders each adapted to hold a series of tubes in parallel relation, the tubes in one work holder being in alignment with those in the other; a series of arbors arranged between the work holders; a series of bearing bars one at each end of each arbor in alignment with the work holders; spindles journaled in the bearing bars and connected with the arbors; and means for reciprocating the arbors and bearing bars.

14. In a polishing machine, the combination of two work holders each adapted to hold a series of tubes in parallel relation, the tubes in one work holder being in alignment with those in the other; a series of arbors arranged between the work holders; a series of bearing bars one at each end of each arbor in alignment with the work holders; spindles journaled in the bearing bars and connected with the arbors; means for reciprocating the work holders and arbors relatively to each other; and a common means for automatically reciprocating the arbors and bearing bars.

15. In a polishing machine, the combination of a spindle adapted to carry a polishing device; a bearing bar for the spindle in the form of a tube; bearings at the ends of the bearing bar in which the spindle is journaled; and thrust bearings on the bearing bar for sustaining the thrust of the spindle.

16. In a polishing machine, the combination of a spindle adapted to carry a polishing device; a bearing bar for the spindle in the form of a tube; bearings at the ends of the bearing bar in which the spindle is

journalized; thrust bearings on the bearing bar for sustaining the thrust of the spindle; a movable support for the bearing bar; a feed device for actuating said movable support; and a stationary support on which the bearing bar is slidably mounted.

17. In a polishing machine, the combination of two spindles arranged in alinement; an arbor between the spindles for driving the spindles; a bearing bar for each spindle, comprising bearings at its ends in which the spindle is journaled; a thrust bearing for sustaining the thrust of the spindle; supports for said bearing bar and arbor; means for moving said support with the feeding movement to the spindles; and stationary supports on which said bearing bars are slidably mounted.

18. In a polishing machine, the combination of a series of arbors arranged in parallel relation; a single belt for directly driving said arbors; means for reciprocating said arbors; a series of spindles driven by said arbors; and work supports in alignment with said spindles.

19. In a polishing machine, the combination of a series of arbors in parallel relation; a feed frame on which said arbors are mounted; a drive shaft; a pulley slidably mounted on said shaft but locked against rotation thereon; a belt connection between said pulley and said arbors; and a feed mechanism carrying said pulley and arbors in an axial direction.

20. In a polishing machine, the combination of a series of arbors; a removable feed frame on which the arbors are mounted; a machine frame comprising parallel bars on which the feed frame is slidably mounted; a drive pulley for the arbors arranged below the feed frame; and a belt connection between the pulley and the arbors, the strain of said belt operating to hold said feed frame in place on said machine frame.

21. In a polishing machine, the combination of a series of arbors arranged in parallel relation; a feed frame on which said arbors are mounted; a pulley for driving said arbors; a belt connection between said pulley and said arbors; and a feed device for automatically reciprocating said feed frame.

22. In a polishing machine, the combination of a series of arbors arranged in parallel relation; a feed frame on which said arbors are mounted; a drive shaft arranged on the machine; a drive pulley slidably mounted on said shaft but locked against rotation thereon; a belt connection between said pulley and arbors; and means for reciprocating said feed frame and for moving said drive pulley axially on said drive shaft with said feed frame.

23. In a polishing machine, the combination of an arbor; a spindle driven by the arbor; a feed frame on which the arbor is

5 mounted; a drive shaft; a drive pulley slid-
ingly mounted on the shaft but locked
against rotation thereon; a belt connection
between the pulley and the arbor; and means
for automatically reciprocating the feed
frame and with it the arbor and drive pul-
ley.

24. In a polishing machine, the combina-
tion of an arbor; a feed frame on which the
10 arbor is mounted; a drive shaft; a drive
pulley slidingly mounted on the shaft but
locked against rotation thereon; a belt connec-
tion between the pulley and the arbor; feed
drive pulleys slidingly mounted on the
15 drive shaft but locked against rotation
thereon; feed pulleys mounted on the feed
frame; a direct connection between one feed
drive pulley and one feed pulley and a twist
belt connection between the other feed drive
20 pulley and feed pulley; a clutch mechanism
for throwing in and out said feed pulleys; a
feed mechanism driven by said feed pulleys
for reciprocating the feed frame; and means
carried by the feed frame for moving the
25 drive pulley and feed drive pulleys on the
drive shaft with the feed frame.

25. In a polishing machine, the combina-
tion of a series of spindles; an arbor for
driving the spindles; a feed frame carrying
30 the arbor; an automatic feed mechanism
carried by the feed frame; devices for
throwing said automatic feed mechanism
into and out of action; and means manually
operative for actuating the feed frame.

35 26. In a polishing machine, the combina-
tion of a machine frame comprising parallel
bars; leg supports arranged on said bars; a
feed frame slidingly mounted on said bars;
an arbor mounted on the feed frame; a work
40 support arranged on said bars and spindles
driven by said arbor; and means for recip-
rocating said frame on said bars.

27. In a polishing machine, the combina-
tion of a machine frame comprising parallel
45 bars; leg supports for said bars; work
holders arranged on said bars at each end
of the frame; a feed frame slidingly mounted
on said bars; an arbor on said feed
frame; a spindle on each end of the arbor;
50 and means for reciprocating the feed frame.

28. In a polishing machine, the combina-
tion of a machine frame comprising parallel
bars and supporting legs; a feed frame slid-
ingly mounted on said bars; a series of ar-
55 bors mounted on said feed frame; work
holders at each end of said bars adapted to
hold a plurality of tubes; spindles arranged
at each end of each arbor for operating
upon the tubes in the work holder; and
60 means for reciprocating the feed frame.

29. In a polishing machine, the combina-
tion of a machine frame comprising parallel
bars and supporting legs; a feed frame slid-
ingly mounted on said bars; a series of
65 arbors mounted on said feed frame; work

holders at each end of said bars adapted to
hold a plurality of tubes; spindles arranged
at each end of each arbor for operating
upon the tubes in the work holder; means
for reciprocating the feed frame, compris-
70 ing a drive shaft; pulleys slidingly mounted
on said drive shaft but locked against rota-
tion thereon; a belt connection between said
pulleys; and mechanism on the feed frame
for converting the movement of the pulleys
75 into the feeding movement of the frame.

30. In a polishing machine, the combina-
tion of a machine frame comprising parallel
bars and supporting legs; a feed frame slid-
ingly mounted on said bars; a series of 80 arbors mounted on said feed frame; work
holders at each end of said bars adapted to
hold a plurality of tubes; spindles arranged
at each end of each arbor for operating
upon the tubes in the work holder; means
85 for reciprocating the feed frame, compris-
ing a drive shaft; pulleys slidingly mounted
on said drive shaft but locked against rota-
tion thereon; a belt connection between said
pulleys; mechanism on the feed frame for 90
converting the movement of the pulleys into
the feeding movement of the frame; and
apparatus for driving said arbors comprising
a drive pulley slidingly mounted on the
drive shaft but locked against rotation 95
thereon.

31. In a polishing machine, the combina-
tion of a machine frame comprising parallel
bars and supporting legs; a feed frame slid-
ingly mounted on said bars; a series of 100 arbors mounted on said feed frame; work
holders at each end of said bars adapted to
hold a plurality of tubes; spindles arranged
at each end of each arbor for operating
upon the tubes in the work holder; means
105 for reciprocating the feed frame, compris-
ing a drive shaft; pulleys slidingly mounted
on said drive shaft but locked against rota-
tion thereon; a belt connection between said
pulleys; mechanism on the feed frame for 110
converting the movement of the pulleys into
the feeding movement of the frame; appa-
ratus for driving said arbors comprising a
drive pulley slidingly mounted on the drive
shaft but locked against rotation thereon; 115
and devices for moving said pulleys with
the feed frame.

32. In a polishing machine, the combina-
tion of a work support comprising a socket;
a bushing adapted to engage a tube to be 120
polished arranged in the socket; and means
for clamping the bushing in the socket for
holding the work in place.

33. In a polishing machine, the combina-
tion of a work holder, comprising sockets;
screw threaded bushings having their outer
peripheries adapted to fit in said sockets
and their inner peripheries to engage a
screw threaded tube; and clamps for hold-
ing said bushings in said sockets. 125
130

34. In a polishing machine, the combination of an arbor; a spindle driven by the arbor; means for reciprocating the arbor and spindle; a work holder comprising two 5 sockets in alinement; bushings having their outer peripheries adapted to fit in said sockets and to engage a tube at their inner peripheries; and means for clamping said bushings in said sockets.

10 35. In a polishing machine, the combination of a work holder comprising a series of sockets arranged in parallel relation; two bars each bar having a series of sockets with each socket in alinement with a companion 15 socket on the other bar; a series of bushings having their outer peripheries adapted to fit in said sockets and their inner peripheries adapted to engage tubes to be polished; and means for clamping said bushings to said 20 sockets comprising studs extending upwardly from the work holder between the sockets; and clamping plates extending from one bushing to another, said plates being whipped to permit of their turning on the stud and dropping into the spaces between the bushings.

25 In testimony whereof I have hereunto set my hand in the presence of two subscribing witnesses.

30 RUDOLPH CONRADER.
